UNITED STATES PATENT OFFICE.

JAMES A. D. SHEFFIELD AND JOHN C. SHEFFIELD, OF HOUSTON COUNTY, TEXAS.

CULTIVATOR-PLOW.

SPECIFICATION forming part of Letters Patent No. 695,499, dated March 18, 1902.

Application filed October 5, 1901. Serial No. 77,709. (No model.)

To all whom it may concern:

Be it known that we, JAMES A. D. SHEFFIELD and JOHN C. SHEFFIELD, citizens of the United States, residing in the county of 5 Houston and State of Texas, have invented a new and useful Cultivator-Plow, of which the following is a specification.

Our invention is an improved cultivator-plow, especially adapted for cultivating cotton and other crops; and it consists in the peculiar construction and combination of devices hereinafter fully set forth and claimed.

In the accompanying drawings, Figure 1 is a perspective view of a cultivator-plow constructed in accordance with our invention. Fig. 2 is partly a side elevation and partly a sectional view of the same. Fig. 3 is a detail perspective view of one of the adjusting-plates used on the beam for securing the 15 standard brace-links at any desired adjustment of the standards. Fig. 4 is a detail perspective view of one of the clamping-links used for securing the shovels or points to the standards. Fig. 5 is a similar view of one of 20 the foot-blocks used in the same connection.

The beam 1 is preferably made of wood and is provided at its front end with the usual clevis 2. The handles 3 have their front ends connected to opposite sides of the beam by a 25 bolt 4. A rung 5 connects the rear portions of the handles together. A wheel 6 is disposed under the rear portion of the beam and is mounted in a standard 7, which is composed of a pair of bars 7^a, which bear against 30 opposite sides of the beam, are connected thereto by a bolt 8, which passes through openings in said bars and beams, and the upper ends of the said bars 7^a are bent outwardly, as at 9, and provided with adjusting- 35 openings 10. Bolts 11, which are fitted in openings with which the handles 3 are provided, pass through appropriate openings 10 and secure the said standards 7 at any desired angle with relation to the beam, and this construction and combination of devices also 40 enables the handles to be adjusted vertically, so that their rear ends may be disposed at any desired height to suit the plowman. The bars 7^a have adjusting-openings 12 in their 45 lower portions to receive the bolt 13 or spindle on which the wheel 6 revolves, and hence

the latter may be adjusted vertically in the standard 7, as will be understood.

Our improved cultivator-plow is provided with a plurality of standards 14 to carry shovels or points 15, which may be of any suitable construction and shape. The standards are disposed one in advance of the other and in line with each other and with the wheel 6. Each of the said standards is composed of a 55 pair of bars 14^a, which are connected together at their lower ends and the upper ends of which are bent outwardly in opposite directions, bear against opposite sides of the beam 1, and are secured thereto by bolts 16, which pass 60 through openings in the upper portions of said standard-bars at points above and below the beam, hence clamping the standards to said beam without weakening the latter by passing the bolt therethrough. By loosening the 65 nuts on the said clamping-bolts the said standards may be adjusted to any desired inclination, as will be understood.

On the beam 1, at suitable distances in advance of the respective standards 14, are secured adjusting-plates 17. The said adjusting-plates have their upper sides corrugated transversely, as at 18, and are provided with holes 19 for screws which are employed to 70 secure the said adjusting-plates on the beam. 75

Brace-links 20, each of which comprises a pair of bars 21, have their rear ends pivoted between the bars 14^a of the standards 14 by bolts 22. The said brace-links have their respective bars clamped on opposite sides of 85 the beam by bolts 23, which pass below the beam, and bolts 24, which pass above the beam, and engage appropriate corrugations in the adjusting-plates 18. The said bolts and the said adjusting-plates enable the said 90 brace-links to be shifted longitudinally on the beam to dispose and secure the standards 14 at any desired angle.

Foot-blocks 25 are secured between the lower ends of the bars 14^a of each standard 95 14 by bolts 26. The said foot-blocks have laterally-extending shoulders 27 at their lower front corners, which bear on the front edges of the standard-bars 14^a. The shovels or points 15 are disposed on the front side of the 100 said foot-block and at their upper portions bear against the front sides of the standards

14. Clamping-links 28, which are provided at their front ends with T-heads 29 and at their rear ends with laterally-extending eyes 30, are disposed between the bars 14^a of standards 14, and their T-heads 29 are adapted to bear on the upper sides of the said shovels or points. The bolts 31, which are employed to clamp the shovels or points to their standards, pass between the bars of the latter through 10 the eyes 30 of the clamping-links, and their nuts or taps 32 bear against the rear sides of the said eyes 30. Hence the said bolts coöperate with the said clamping-links to secure the points or shovels against vertical 15 placement on the standards and enable the said points or shovels to be adjusted vertically and clamped to the standards at any desired point.

By attaching appropriate points or shovels 20 to the standards our improved plow may be used for barring off between the rows of plants and sweeping earth up toward the plants when cultivating a cotton crop. Our improved plow may be also used, when provided with appropriate points or shovels, for 25 bedding and listing the soil or for banking or breaking out the rows. It will be understood that by appropriately adjusting the standards and the wheel 6 the points or shovels may 30 be caused to run in the soil to any desired depth. The wheel 6, which operates in the furrows in rear of the points or shovels, materially lessens the labor to the plowman. At the end of a row, before turning, the 35 handles should be depressed to elevate the points or shovels, thereby supporting the plow entirely upon the wheel 6, when the plow may be readily turned without appreciable effort on the part of the plowman. The wheel 6, 40 which operates in rear of the plow, also enables the plow to be readily moved to any part of the field without permitting the points or shovels to cut the surface of the soil. By having the points or shovels and the wheel

in line with each other and directly in the 45 line of draft under the beam the plow is enabled to run very steadily and evenly without deviation from a straight line and is adapted to be readily guided.

Our improved plow is exceedingly cheap 50 and simple, is very strong and durable, and is entirely practical and efficient in operation.

Having thus described our invention, we claim—

1. In a plow, the combination of a beam, 55 handles pivotally connected at their lower front ends thereto, a standard comprising a pair of bars, disposed on opposite sides of the beam and pivotally connected thereto, the upper ends of said bars being adjustably attached to said handles, and a wheel mounted between the lower portions of said bars, substantially as described.

2. In a cultivator-plow, the combination of a beam, a standard having its upper end 65 forked, to provide arms which bear against opposite sides of the beam, clamping-bolts connecting said arms above and below the beam, whereby the upper end of the standard is adjustable longitudinally of the beam, an 70 adjusting-plate on the latter, notched on its upper side, a brace-link connected to said standard, extending forwardly and upwardly therefrom and provided with arms which bear against opposite sides of said beam, 75 and bolts connecting said arms and extending transversely above and below the beam, the upper of said bolts engaging said notched adjusting-plate, substantially as described.

In testimony that we claim the foregoing as 80 our own we have hereto affixed our signatures in the presence of two witnesses.

JAMES A. D. SHEFFIELD.
JOHN C. SHEFFIELD.
